UNITED STATES PATENT OFFICE.

JAMES MADISON WALTERS, OF LOS ANGELES, CALIFORNIA.

DISPLAY-STAND.

1,351,817.

Specification of Letters Patent. Patented Sept. 7, 1920.

Application filed February 6, 1920. Serial No. 356,610.

To all whom it may concern:

Be it known that I, JAMES MADISON WALTERS, a citizen of the United States, and a resident of Los Angeles, in the county 5 of Los Angeles and State of California, have invented certain new and useful Improvements in Display-Stands, of which the following is a specification.

My invention is an improvement in display stands, and has for its object to provide a new and improved form of stand adapted for displaying evening gowns and lingerie, underwear and the like, wherein the fixture is so constructed that it will be 15 hidden by the garment displayed.

In the drawings:

Figure 1 is a front view of the improved stand;

Fig. 2 is a similar view of a portion of 20 the stand, showing other attachments;

Fig. 3 is a plan view of a shoulder bar of modified form;

Fig. 4 is a vertical section through the triple connector.

25 In the embodiment of the invention shown a suitable standard is provided, in the present instance consisting of a base section 1 and an upper section 2, which is mounted to slide in the base section. A collar 3 is secured to the base section at its top, the section 2 sliding through the collar and a set screw 4 is threaded through the collar into engagement with the section 2 to limit the sliding movement thereof.

35 The base section has a base 5 of suitable size and shape, and the upper end of the section 2 is provided with a triple connector. This connector 6, as shown more particularly in Fig. 4, is in the form of a head, 40 having oppositely arranged alined internally threaded recesses 7 and 8, the recess 7 being adapted to receive the upper end of the section 2 of the standard, while the recess or socket 8 is for a purpose to be pres- 45 ently described.

A series of attachments is provided, each carrying a triple connector 6 for engaging the section 2 of the stand. The attachment shown in Fig. 1 is a substantially yoke 50 shaped member, consisting of a body 9 and

arms 10 extending at right angles from the body. The body passes through an opening in the head and is rigid with the head, the arrangement being such that when the head is connected with the section 2 of the standard the arms will be vertical. Each of these arms has an outwardly bent portion 11 at its extremity, each of the said portions being threaded, and they are designed to engage threaded sockets 12 on 60 shoulder supports 13. Each of these shoulder supports, as shown in Fig. 1, is an arc shaped bar having its ends rounded.

In Fig. 3 is shown another form of attachment, consisting of a bar 14 having its 65 ends curled, as shown at 15, in opposite directions.

In Fig. 2 there is shown another form of attachment, especially designed for displaying articles having narrow supporting ribbons. This attachment is in the form of a 70 yoke comprising a body 16 and arms 17, each arm having the outwardly bent portion 18 at its extremity corresponding to the portions 11 of the attachment of Fig. 75 1. These portions 18 are threaded and they may engage sockets or shoulder pieces.

In Fig. 2 the shoulder pieces are omitted, the outwardly bent portions engaging the ribbons directly. In the attachment shown 80 in Fig. 2 the arms are nearer each other and the body is curved, so that the attachment as a whole is curved from end to end, being U-shaped. If desired, the bar shown in Fig. 2 may be connected with the socket 85 8 of the triple connection. This bar 19 has one end threaded and is provided at the other end with a substantially triangular open loop 20. This loop might support some other article, as, for instance, a hat or 90 cap.

As shown in Fig. 1, the shoulder pieces are used when the shoulder straps of the garment are of such width that they will 95 cover the shoulder pieces. When the shoulder straps are narrow the attachment shown in Fig. 2 is used, or the ornamental shoulder pieces shown in Fig. 3 may be used.

I claim:

A display stand comprising a standard 100

and an attachment for connection with the standard for supporting garments having shoulder straps, the attachment comprising a yoke shaped member consisting of a body 5 having means for engaging the top of the standard, and arms extending upwardly from the body and spaced apart to register with the shoulder straps of the garment to be supported and of a length to hold the

garment with the upper line of the bosom 10 thereof above the body of the attachment, each arm having a shoulder-piece detachably connected therewith, said shoulder-pieces being inclined outwardly and downwardly and each extending on both sides 15 of each arm of the yoke at its end.

JAMES MADISON WALTERS.
